CLAIM

The ornamental design for an automated vending machine for custom engraved products, as shown and described.

DESCRIPTION

FIG. 1 is a perspective view of a automated vending machine for custom engraved products showing our new design;

FIG. 2 is a front elevational view thereof;

FIG. 3 is a side elevational view thereof, the opposite side is a mirror image thereof; and,

FIG. 4 is a top plan view thereof.

The undisclosed bottom plan view is plane and unornamented.
